(57) **CLAIM**

The ornamental design for a vehicle front winch bumper, as shown and described.

DESCRIPTION

FIG. 1 is a left upper perspective view of a vehicle front winch bumper, in use condition showing my new design; FIG. 2 is a left side elevational view thereof, the right side being a mirror image;

FIG. 3 is a front elevational view thereof;

FIG. 4 is a rear elevational view thereof;

FIG. 5 bottom plan view thereof; and,

FIG. 6 is a top plan view thereof.

The dash-dash even broken lines illustrate and surround portions of the vehicle front winch bumper that form no part of the claimed design. The “long dash-short dash-short dash” broken lines shown in the drawings illustrate vehicle environmental subject matter which forms no part of the claimed design.
